UNITED STATES PATENT OFFICE,

CHARLES F. HAKE, JR., OF CINCINNATI, OHIO.

MACHINE FOR RENOVATING SHEET METAL.

1,198,346.

Specification of Letters Patent. Patented Sept. 12, 1916.

Application filed January 24, 1916. Serial No. 73,798.

To all whom it may concern:

Be it known that I, CHARLES F. HAKE, Jr., a citizen of the United States of America, and resident of Cincinnati, county of 5 Hamilton, State of Ohio, have invented certain new and useful Improvements in Machines for Renovating Sheet Metal, of which the following is a specification.

This invention relates to a machine for 10 renovating sheet metal, and particularly to a machine for cleaning and straightening the tin plates employed in the manufacture of tin cans.

In the manufacturing operations necessary to produce the containers for certain classes of goods, the surface of the tin is painted, lithographed or printed previous to its being cut and made up into cans. In this operation the sheets have to be handled very 20 carefully to avoid marring them before they are dried, as well as to avoid scratching them and thus damaging their finish after they are dried. Frequently, however, the dried and finished sheets become blistered, rubbed, 25 scratched or bent, before being cut up and made into cans. This necessitates discarding the damaged sheets and selling them as scrap at a fraction of their cost. It is to overcome this great waste and the consequent loss of money, time and labor occasioned thereby, that I have devised the machine forming the subject matter of this invention.

The object of my invention is to produce 35 a machine for cleaning and straightening damaged sheets of lithographed, printed or painted tin. This and other objects are attained in the machine described in the following specification and illustrated in the 40 accompanying drawings, in which—

Figure 1 is a plan view upon a reduced scale, of a machine embodying my invention. Fig. 2 is a side elevation upon a reduced scale, of the machine illustrated in Fig. 1. 45 Fig. 3 is a plan view upon an enlarged scale, of the scrubbing and primary sheet straightening mechanism of the machine embodying my invention. Fig. 4 is a side elevation upon an enlarged scale of the portion of the machine shown in Fig. 3, certain parts being broken away. Fig. 5 is a plan view upon an enlarged scale, of the sheet rinsing mechanism, the wringer and the secondary straightening or primary planishing mechanism.

Fig. 6 is a sectional view upon an enlarged scale of the mechanism disclosed in Fig. 5, certain parts being broken away and shown in section for clearness of illustration. Fig. 7 is a sectional elevation upon an enlarged scale of the sheet drying or secondary planishing mechanism of the machine embodying my invention. Fig. 8 is a transverse sectional elevation of the scrubbing mechanism, disclosed in Fig. 3 and taken upon line 8—8 thereof. Fig. 9 is a fragmental 65 sectional view of the primary sheet straightening mechanism, taken on the line 9—9 of Fig. 3. Fig. 10 is a sectional view of the scrubbing mechanism taken on the line 10—10 of Fig. 3. Fig. 11 is a sectional view 70 of the sheet wiping and scraping mechanism, taken on the line 11—11 of Fig. 3. Fig. 12 is a sectional view of additional scrubbing and wiping or scraping mechanism, and taken on the line 12—12 of Fig. 75 3. Fig. 13 is a fragmental plan view of a modified form of sheet straightening mechanism adapted to be used in place of the sheet straightening mechanism disclosed in Fig. 9. Fig. 14 is a sectional view taken on line 80 14—14 of Fig. 13.

My sheet renovating machine consists of three principal divisions, the first of which is the unit A embodying the primary sheet straightening mechanism and the scrubbing and wiping or scraping mechanisms. Next to this unit and operatively connected therewith is the unit B which embodies the rinsing, wringing, and secondary sheet straightening or primary planishing mechanism. 85 Following the unit B and co-operating therewith is the unit C, constituting the drier or secondary planishing mechanism, and following this is the final planishing or polishing mechanism D through which the 90 sheets pass in the final step taken in turning out sheets which have been thoroughly cleaned, dried, and straightened for refinishing.

In describing my invention I will take up 100 the units in the order above indicated, with the elements contained in each unit, described in sequence of their operation upon the sheets passing through the machine.

Unit A consisting of the primary straightening mechanism and the scrubbing mechanism, is built upon a frame-work 14 consisting of a bed 14^a supported by legs 14^b. The

2

bed is built in the shape of a reservoir to be presently more fully described, with a series of journal bearings spaced along its sides for a series of sheet rolls 16 between and by means of which the sheet is passed through this unit of the machine. As the sheet is started in its passage through the machine, the first set of sheet rolls brings it into engagement with a series of fingers 17 rotatively mounted upon the shaft 18 of the upper feed roller of the first set. The blocks 19 which carry the fingers 17 are connected with levers 20 secured to a rotatively mounted shaft 21, by means of links 22. The shaft 21 extends transversely of the machine and is provided at one end with a pawl 23 adapted to be moved into engagement with the teeth of a ratchet 24 secured to the shaft 25 of straightening rolls or bars 26, between which the sheet is passed. These bars are corrugated as shown in Figs. 3 and 9, and are adapted to straighten turned-over-edges of the sheet passing between them, when they are held stationary. However, these rolls are rotatively mounted in bearings 27 formed on the sides of the reservoir, one end of the shaft 25 extending through one of the bearings and having a pinion 28 frictionally secured thereto by means of a yielding tension device 29, for the purpose of driving the rolls when a sheet is passing between them and for permitting of the rolls being stopped when a sheet has passed from beneath the fingers 17. Both the upper and lower straightening rolls are provided with pinions which intermesh, so that both rolls will be rotated in unison, the pinions being operatively connected with the mechanism employed for rotating the shafts 18 of the first set of feed rolls. The fingers 17 normally extend below the line of passage of each sheet as it passes between the first set of feed rolls and the sheet straightener, so that when the sheet engages the fingers they will be lifted and thus cause the levers 20 to lift the pawl 23 out of engagement with the teeth of the ratchet 24 and permit of rotation of the corrugated rolls. As soon however, as the edge of the sheet is reached, the fingers drop and stop the straightener rolls 26, thus causing the sheet which has entered between the second set of sheet rolls, to be pulled between the stationary corrugated straightening rolls 26, the pawl 23 having been brought into engagement with the teeth of the ratchet 24 to hold the corrugated rolls stationary, after the fingers 17 have dropped from the edge of the sheet. In this operation any turned up edges of the sheet, will be straightened out and prevented from becoming creased or folded as would have occurred had the sheet been passed entirely through the machine without having been straightened first. It will be noticed that

the sheet rolls which operate to pull the sheet between the straightening rolls are so formed as to grip the entire surface of the sheet and thus prevent the sheets slipping when the straightening rolls are held stationary by the pawl 23. This is for the reason that the straightening rolls exert a tension on the sheet which smoothes out any wrinkles or turned over edges or corners. The first set of sheet rolls 31 consists of two pairs of disks having yielding tires with set screws 32 for adjusting them along their mounting shafts 18 in order to accommodate themselves to different widths of sheets. The mechanism is so designed that it is preferably the last edge of each sheet that is subjected to the ironing or straightening effect of the rolls 26 when they are stopped.

Following the sheet rolls 30 is a scrubbing mechanism consisting of a transversely reciprocating brush 33 which moves rapidly across the surface of the sheets passing through the machine. This brush is reciprocated by means of a connecting rod 34 having rotative connection with a crank 35 mounted on a shaft 36 journaled in bearings 37 secured to the side of the frame of this portion of the machine. Rotation of the shaft 36 and consequent reciprocation of the brush 33 is secured by mechanism to be more fully hereinafter described. In order to secure sufficient pressure of the brush 33 upon the sheet passing through the machine and in order at the same time to permit a free movement of the brush across the sheet without in any way affecting the ease of drive of the crank 35 and connecting rod 34, I have provided arms 38 secured to the brush carrier 33 and which extend beyond the sides of the frame and which are alined over arms 39 bolted to the sides of the frame immediately beneath the arms 38. Connecting the arms 38 and 39 are spring bolts 40, the bolts being pivotally mounted at the ends of the arms 39 so as to be free to swing therein, and at their upper ends are provided with springs 41 and a suitable adjustment means which bring the springs into tension against the arms 38 of the brush and consequently force the brush onto the surface of the sheets. With this pressure regulating device the brush may move freely across the sheet and at the same time be subjected to a substantially uniform pressure thereon. In addition to this means of adjusting the pressure of the brush upon the sheets, I have provided adjusting screws 33^a in the backs of the brushes, by means of which the brush blocks 33^b (see Fig. 10) may be moved toward or from the surfaces of the sheets, as desired. The brush blocks I preferably provide in sections, so that the brush may be made to extend only over the width of the sheets passing through the machine, thus making them adjustable for the differ-

ent widths of sheets which may be passed beneath them. Above the brush I preferably locate a perforated water supply pipe 42, the perforations of which direct a spray 5 of water across the brush for scrubbing the sheets.

Immediately following the reciprocating brush 33 is a set of rubber tired feed rolls 43 which grip the sheet after its having 10 passed the brush 33 and force it beneath a sheet wiping or scraping device 44. This wiping device consists of a pivotally mounted board 45 which is mounted at its upper edge so that its lower edge is free to bear 15 against the entire width of the upper surface of the sheets passing through the machine. Its lower edge is however, provided with a rubber or brass strip 45^a which bears against the sheet and wipes or scrapes off 20 the paint, ink, and other material loosened by the brush. This device is held against the sheet under spring tension by means of springs 46 mounted on bolts 47 secured to the transversely extending bar 48 upon 25 which the board is pivotally mounted. Suitable adjustment means is provided on the bolt for regulating the tension of the springs 46 and consequently the pressure of the board 45 with which the strip 45^a is held 30 into engagement with the surface of the sheet.

Immediately after having passed the wiping device 44 the sheet passes between another set of feed rolls 49 which are constructed in the same manner as the feed rolls 31 and 43. The feed rolls 49 pass the sheet beneath another brush 50 similar in construction to the brush 33 and operate in the same manner by means of a connecting 40 rod 51 and a crank 52 on the opposite end of the shaft 36. This brush is tensioned in the same manner as the brush 33 and is provided with a water spray 53 located in the same position and for the same purpose as the spray 42. After having passed the second reciprocating brush 50 the sheet is drawn between another set of rubber tired feed rolls 54 which pass it in turn over a rapidly rotating cylindrical brush 55 located beneath the 50 sheet and partially submerged in water for the purpose of scrubbing its under surface. This brush is held in yielding engagement with the under faces of the sheets by means of a spring 55^a secured thereto and adjustably supported at its upper end by an arm 55^b extending from one side of the adjacent feed roll journal bracket. After having passed this brush the sheet is brought beneath an additional wiping or scraping 60 device 56 constructed in the same manner and for the same purpose as the wiping device 44, but to remove substantially all final traces of paint or ink not previously removed and which have been loosened by the 65 brush 50. After passing this device the

sheet passes through the last set of feed rolls 57 with which this portion of the machine is provided. These feed rolls in turn pass the sheet onto supporting fingers 58 extending over the space between the unit A and 70 the rinsing unit B.

The sheet in its passage through unit A is supported between the feed rolls and beneath the brushes 33 and 50 as well as the wiping or scraping devices 44 and 56, by 75 means of a series of small table sections 59 which are secured to lugs 60 formed on the journal bearing brackets 15 of the feed rolls. The top surfaces of the table sections are in alignment with the point of contact of the feed rolls and form as it were a continuous table surface. However, at points between the table sections where the upper and lower feed rolls engage one another, as well as at the ends of the reciprocating brushes 33 and 80 50 and at the point where the brush 55 is located, openings 61 are formed. These openings are for the purpose of permitting the water from the spray pipes 42 and 53 and the removed paint and ink to pass into the 85 reservoir 64 forming the bed of the unit A. This reservoir is of sufficient depth to permit the water to accumulate therein to the depth of several inches so that the paint and ink removed from the sheets may settle to the 90 bottom thereof before the water passes therefrom. Since drainage of the materials removed from the sheets is prohibited by ordinances in most cities, from being passed into the sewers, a device for preventing this and 95 yet at the same time of permitting escape of water from the reservoir, is employed. This device consists of an overflow pipe 65 which extends upwardly through the bottom of the reservoir with its upper end located at a 100 point above the bottom thereof and adjacent to the top, but sufficiently below the top to prevent the reservoir overflowing. When the waste water accumulates in the reservoir 105 to the top of the pipe it will overflow into the pipe and pass therethrough into the sewers. The heavier paint and other materials removed from the sheets will however, settle to the bottom before the water overflows into the pipe 65. A suitable trapping device 66 is mounted at the upper end of the pipe 65 as is usual in all sewer pipe connections. The pipe 65 is located in a stuffing box 67 so that it may be reciprocated 110 therein in order to regulate the distance between the bottom of the reservoir and the upper end of the pipe and thus regulate the depth of waste water contained in the reservoir. In order to facilitate reciprocation of the pipe for this purpose a mechanism 68 is 115 employed. This mechanism consists of a worm 69 meshing with the teeth of a gear segment 70 which is operatively connected with a collar 71 clamped to the pipe 65, by means of an arm 72 and a link 73. The 120 125 130

worm is rotated by means of a hand wheel 74 mounted on the shaft 75 to which the worm is secured. After the accumulation of paint and other material scrubbed from the sheets has become such that the reservoir is substantially full, hand holes 92 and 93 are opened for permitting the reservoir to be emptied into buckets and to permit the contents to be suitably disposed of.

- 10 The mechanism for driving the feed rolls, the reciprocating brushes, the rotating brush, and the straightening devices, will be described. Each of the feed rolls is provided with a pinion 76, the pinions of each upper 15 and lower roll of each side intermeshing so that the rolls will be driven in the same direction at their point of contact. Outside these pinions and preferably secured to the shafts of the lower feed rolls are gears 77 20 which mesh with a series of worms 78 spaced along a drive shaft 79 journaled in bearings 80 longitudinally aligned on the side of the reservoir 14. Secured to the end of the shaft 79, which is located at the delivery 25 end of the unit A is a sprocket 81 and a drive pulley 82 from which the machine receives its driving power. The sprocket 81 is connected by the chain 83 with a sprocket 84 which is secured to a shaft 85 extending 30 on the opposite side of the machine to the point where the crank shaft 36 which affects reciprocation of the brushes 33 and 50, is rotatively mounted. Power from the shaft 85 is communicated to the crank shaft 36 by 35 means of a series of intermeshing gears 86, 87 and 88. In order to drive the straightening rolls 26 a gear 89 mounted on one of the shafts 18 of the first set of feed rolls 31 is provided for the purpose of meshing with 40 the pinion 28 which is frictionally connected with the shaft 25 of the upper one of the straightening rolls. At the drive shaft end of the bed intermeshing pinions 90 and 91 are provided for permitting of the rolls being 45 driven in unison. The means employed for driving the rotating brush 55 which scrubs the under surface of the sheets consists of two spiral gears 94 which communicate power from the driving shaft 79, 50 transversely of the machine to intermeshing gears 95 located on the opposite side of the bed, one of which is secured to the shaft of the brush 55.
- 55 A modified form of sheet straightening device is illustrated in Figs. 13 and 14, this device consisting of two bars 96 and 97 bent at an angle with the apex located in the center of the bed and extending in the direction from which the sheets are coming. The 60 bars are spaced apart a sufficient distance to permit of the passage of the sheets between them. In this construction the action is to cause the turned up corners and other wrinkled or turned over portions of the sheet, to be straightened out, as shown in

dotted lines in Fig. 13, the bars acting as a plow for pushing over the turned up edges and thus straightening the sheet. In this construction the gears 28 and 89, and fingers 17, as well as the pawl 23 and the friction 70 device 29, are eliminated.

The mechanism for rinsing the sheets will now be described.

The rinsing mechanism, the wringing mechanism, and the primary planishing mechanism, are embodied in the single unit B. After the sheets have been passed from the unit A onto the fingers 58 thereof, they are dropped onto a series of rolls 96 located materially above a set of conveyer chains 97 80 passing from sprockets 98 secured to a shaft 99 extending transversely of the frame of the unit B, and over a series of sprockets 100 secured to a shaft 101 also extending transversely of the frame of the unit B. The 85 frame of the unit B is made into a reservoir 102 adapted to contain rinse water, and the shafts 99 and 101 are journaled in bracket bearings 103 and 104 respectively, secured to the inner sides of the reservoir. The 90 bracket 104 is however, located adjacent to the bottom of the reservoir while the bracket 103 is located adjacent to the top of the reservoir. This gives the chain 97 an inclination 95 from the entering end of the reservoir downwardly toward its center, so that the sheets will be brought into the rinse water. The purpose of locating the rolls 96 some distance above the receiving ends of the chains 97 is to permit the edge of the sheet to bend 100 before it contacts the receiving ends of the chains and thereby dip the forward edge of the sheet under the water and thus prevent its planing across the surface of the water, which would prevent its being properly 105 rinsed. Above the upper end of the conveyer chains 97 is located a spray pipe 105 which is arranged to throw a spray onto the sheets dipping into the bath or just previous to entering it. This is for the purpose 110 of forcibly dislodging any clinging particles of solid material which may have been loosened from their surfaces and which may have escaped the wiping or scraping devices 44 and 56, so that when the sheet is immersed in the rinse water the solid material will be floated therefrom and as a sheet is passed farther into the bath it will be moved from beneath the floating material 115 removed therefrom to cleaner portions of the 120 rinse water. At the opposite end of the reservoir 102 a shaft 106 carrying sprockets 107 is located, the shaft being journaled in much the same manner as the shafts 99 and 101. Over these sprockets pass conveyer 125 chains 107^a which at their lowest points pass over sprockets 108 secured to the shaft 101 adjacent to the sprockets 100 over which the conveyer chains 97 pass. The chains 107^a are provided for removing the sheets from 130

the bath the sheets having passed down the conveyer chains 97 to the bottom of the bath. The bottom of the reservoir 102 of the rinsing mechanism is provided with a drain pipe 140 which is provided for suitably draining the reservoir. At the end of the reservoir a small drip pan 141 which is attached thereto and which communicates by means of an elbow pipe 142 with another drain pipe 143 is provided beneath the wringer and planishing rolls for receiving the water dropping therefrom. The drain pipes 140 and 143 may be suitably closed by means of stoppers or similar devices.

Connecting the shaft 106 and the shafts 109 of a set of sheet rolls 110 located over the edge of the reservoir, are a series of gears 111, 112, 113, 114 and 115 through which power from the shafts 109 is communicated to the shaft 106 for driving the conveyer chains 107 and 97. These feed rolls 110 pass the sheet from the conveyer chains 107 onto a series of fingers 116 which extend therefrom to the wringer and planishing rolls 117. The rolls 117 are preferably made of a suitable material, such as nickel steel, which will withstand great pressure and act as planishing rolls as well as wringing rolls for squeezing any remaining moisture from the sheets. If however, the planishing effect is not desired, these rolls may be of yielding material such as rubber which will act solely as a wringer for drying the sheets. The shaft 118 carrying one of the wringing and planishing rolls is provided with a sprocket 119 over which passes a chain 120 which passes over a sprocket 121 secured to one of the shafts 109 carrying the feed rolls 110. At the opposite end of the shaft 118 a sprocket 122 is provided, over which a chain 123 which extends to a sprocket 124 on a shaft of the last set of feed rolls 57 of the unit A, passes. This chain 123, by this means communicates driving power to the sprocket 122 and consequently to the connected mechanism just described which causes operation of the rinsing, wringing, and planishing mechanisms comprising the unit B. The sheets having passed from the planishing rolls, are then passed through the drying or secondary planishing mechanism comprising the unit C. This mechanism consists of an oven having a series of gas burners 125 located beneath a hot plate 126 over which the sheets pass in their travel through the drying mechanism. Over this hot plate is a cover plate 127 between which and the hot plate the sheets are adapted to pass. In order to convey these sheets over the hot plate and to prevent their contact therewith, a series of chains 128 are provided, these chains passing over sprockets 129 and 130 located at each end of the oven. The respective sprockets 129 and 130 are mounted on shafts 131 and 132, the shaft 132 having a sprocket 133 at one end, over which passes a chain 134 which passes at its opposite end over sprocket 13 secured to the shaft 118 to which the sprocket 122 of the planishing rolls is secured. By this means the conveyer chains 128 of the drying mechanism, are driven. From the oven the sheets are then removed in a substantially finished condition. If it be desired to carry the finishing- or planishing operation still further, for the purpose of removing any traces of material on the sheets, such as dust left after the secondary planishing operation, as well as to give the sheets a polished surface, I have provided the unit D, which consists of a series of buffing rolls 144, 145 and 146, which are preferably covered with sheep skin, and which rotate at a high rate of speed. Feed rolls 147 are employed for feeding the sheets between the rolls 144 and 145, and feed rolls 148 are employed for feeding the sheets between the rolls 145 and 146. The rolls 147 and 148 are, however, located on opposite sides of the rolls 144, 145 and 146, a receiving and directing platform 149 being employed for catching the sheets delivered from the rolls 144 and 145, and then delivering them to the feed rolls 148.

Suitable mechanism such as the conveyer belt 136 at the entering end of the unit A, and similar means at the delivery end of the unit D, are provided for conveniently feeding the sheets to and delivering them from the machine. At one side of the conveyer 136 I preferably locate a gage plate 138 which is adjustable on cross bars 139 so that it may be positioned in a manner such that the sheets will be fed evenly through the machine, for the varying sizes which may have to be passed therethrough.

Before passing the sheets through the machine they are preferably treated in a lye bath for the purpose of softening the paint and other material contained thereon in order that the brushes may easily remove these materials. The operation of the machine upon the sheets is obvious from the above description and therefore needs no elaboration, but in order to aid in more clearly understanding the reason for providing more than one scrubbing device which moves in more than one direction over the same side of the sheets, and for providing but one scrubbing device for moving in but one direction over the other side of the sheets, it may be explained that the tin sheet used in the manufacture of painted, printed or lithographed cans, is lithographed, painted or printed on but one side. It is this side which is operated on by the reciprocating brushes and the wiping devices, since the opposite side merely needs a slight scrubbing in order to remove any traces of material which may be clinging.

thereto for which purpose the rotating brush 35 is provided.

Having thus described my invention, what I claim is;

5. 1. In a machine for renovating metal sheets, the combination of a sheet straightening mechanism consisting of two straightening bars adapted to permit a sheet to pass between them, a scrubbing mechanism, a wiping mechanism, a rinsing mechanism consisting of a reservoir, and a conveyer for immersing sheets into a bath contained in the reservoir and for removing them therefrom, wringing, planishing, and drying mechanisms arranged for passage of sheets therethrough and substantially in the order named. 70
10. 2. In combination in a machine for renovating metal sheets, a sheet straightening mechanism consisting of two straightening bars adapted to permit a sheet to pass between them, a scrubbing mechanism consisting of a brush, and means for moving the brush over the sheet passing in engagement therewith, a wiping mechanism, a rinsing mechanism consisting of a reservoir, and a conveyer for immersing sheets into a bath contained in the reservoir and for removing them therefrom, and wringing, planishing, and drying mechanisms arranged for passage of sheets therethrough and substantially in the order named, and a conveyer adapted to carry sheets through the machine and into operative relation with the mechanisms. 75
15. 3. In a machine for renovating metal sheets, the combination of a straightening mechanism, a scrubbing mechanism consisting of a reservoir, and a conveyer for immersing sheets into a bath contained in the reservoir and for removing them therefrom, wringing, planishing, and drying mechanisms following the rinsing mechanism, all of said mechanisms being arranged for passage of sheets therethrough and substantially in the order named. 80
20. 4. In combination in a machine for renovating metal sheets, a sheet straightening mechanism consisting of two straightening bars adapted to permit a sheet to pass between them, a scrubbing mechanism, a wiping mechanism, a rinsing mechanism consisting of a reservoir, and a conveyer for immersing sheets into a bath contained in the reservoir and for removing them therefrom, wringing, planishing, and drying mechanisms following the rinsing mechanism, all of said mechanisms being arranged for passage of sheets therethrough and substantially in the order named. 85
25. 5. In combination in a machine for renovating metal sheets, a sheet straightening mechanism consisting of two straightening bars adapted to permit a sheet to pass between them, a scrubbing mechanism, a wiping mechanism, a rinsing mechanism consisting of a reservoir, and a conveyer for immersing sheets into a bath contained in the reservoir and for removing them therefrom, wringing, planishing, and drying mechanisms following the rinsing mechanism, all of said mechanisms being arranged for passage of sheets therethrough and substantially in the order named. 90
30. 6. In combination in a machine for renovating metal sheets, the combination of straightening, scrubbing, and wiping mechanisms, a rinsing mechanism consisting of a reservoir, and a conveyer for immersing sheets into a bath contained in the reservoir and for removing them therefrom, combined wringing and planishing rolls, and a drying mechanism, said mechanisms and rolls being arranged for passage of sheets therethrough and substantially in the order named. 95
35. 7. In a machine for renovating metal sheets, the combination of straightening, scrubbing, and wiping mechanisms, a rinsing mechanism consisting of a reservoir, and a conveyer adapted to carry sheets through the machine and into operative relation with the mechanisms. 100
40. 8. In combination in a machine for renovating metal sheets, a straightening mechanism, a scrubbing mechanism, a wiping mechanism, a rinsing mechanism consisting of a reservoir, and a conveyer for immersing sheets into a bath contained in the reservoir and for removing them therefrom, combined wringing and planishing rolls, and a drying mechanism, said mechanisms and rolls being arranged for passage of sheets therethrough and substantially in the order named. 105
45. 9. In a machine for renovating metal sheets, the combination of a straightening mechanism, a scrubbing mechanism, a wiping mechanism, a rinsing mechanism consisting of a reservoir, and a conveyer for immersing sheets into a bath contained in the reservoir and for removing them therefrom, combined wringing and planishing rolls, and a drying mechanism, said mechanisms and rolls being arranged for passage of sheets therethrough and substantially in the order named, and a conveyer adapted to carry the sheets into the machine and into operative relation with the mechanisms and the rolls. 110
50. 10. In a machine for renovating metal sheets, the combination of a straightening mechanism, a scrubbing mechanism, a wiping mechanism, a rinsing mechanism consisting of a reservoir, and a conveyer for immersing sheets into a bath contained in the reservoir and for removing them therefrom, a wringing mechanism, a planishing mechanism, and a drying mechanism, all of said mechanisms being arranged for passage of sheets therethrough and substantially in the order named. 115
55. 11. In a machine for renovating metal sheets, the combination of a straightening mechanism, a scrubbing mechanism, a wiping mechanism, a rinsing mechanism consisting of a reservoir, and a conveyer for immersing sheets into a bath contained in the reservoir and for removing them therefrom, a wringing mechanism, a planishing mechanism, and a drying mechanism, all of said mechanisms being arranged for passage of sheets therethrough and substantially in the order named. 120
60. 12. In a machine for renovating metal sheets, the combination of a straightening mechanism consisting of two straightening bars adapted to permit a sheet to pass between them, a scrubbing mechanism, a wiping mechanism, a rinsing mechanism consisting of a reservoir, and a conveyer for immersing sheets into a bath contained in the reservoir and for removing them therefrom, combined wringing and planishing 125
65. 13. A machine for renovating metal sheets, comprising a straightening mechanism, a scrubbing mechanism consisting of a brush, and means for moving the brush over a sheet passing in engagement therewith, a wiping mechanism, a rinsing mechanism consisting of a reservoir, and a conveyer for immersing sheets into a bath contained in the reservoir and for removing them therefrom, combined wringing and planishing 130

rolls, and a drying mechanism following the rolls, all of said mechanisms and the rolls being arranged for passage of sheets therethrough and substantially in the order named.

10. In combination in a machine for renovating metal sheets, a sheet straightening mechanism consisting of two straightening bars adapted to permit a sheet to pass between them, a scrubbing mechanism, a wiping mechanism, a rinsing mechanism consisting of a reservoir, and a conveyor for immersing sheets into a bath contained in the reservoir and for removing them therefrom, combined wringing and planishing rolls, a drying mechanism, said mechanisms being arranged for passage of sheets therethrough and substantially in the order named, and a conveyor adapted to carry sheets through the machine and into operative relation with the mechanisms and the rolls.

11. In a machine for renovating metal sheets, the combination of a straightening mechanism, a scrubbing mechanism consisting of a brush, and means for moving the brush over a sheet passing in engagement therewith, a wiping mechanism, a rinsing mechanism consisting of a reservoir, and a conveyer for immersing sheets into a bath contained in the reservoir and for removing them therefrom, combined wringing and planishing rolls, and a drying mechanism, said mechanisms and rolls being arranged for passage of sheets therethrough and substantially in the order named.

40   12. A machine for renovating metal sheets, comprising a straightening mechanism, a scrubbing mechanism consisting of a brush, and means for moving the brush over a sheet passing in engagement therewith, a wiping mechanism, a rinsing mechanism consisting of a reservoir, and a conveyer for immersing sheets into a bath contained in the reservoir and for removing them therefrom, combined wringing and planishing rolls, a drying mechanism, said mechanisms and rolls being arranged for passage of sheets therethrough and substantially in the order named, and a conveyer adapted to carry the sheets through the machine and into operative relation with the mechanisms and rolls.

13. In combination in a machine for renovating metal sheets, a straightening mechanism consisting of two straightening bars adapted to permit a sheet to pass between them, a scrubbing mechanism consisting of a brush, and means for moving the brush over the sheet passing in engagement therewith, a wiping mechanism, a rinsing mechanism consisting of a reservoir, and a conveyor for immersing sheets into a bath contained in the reservoir and for removing them therefrom, combined wringing and

planishing rolls, a drying mechanism, said mechanisms and said rolls being arranged for passage of sheets therethrough and substantially in the order named, and a conveyor operatively associated with the mechanisms for passing sheets consecutively therethrough. 70

14. In combination in a machine for renovating metal sheets, a straightening mechanism consisting of two straightening bars 75 adapted to permit a sheet to pass between them, a scrubbing mechanism consisting of a brush, and means for moving the brush over the sheets passing in engagement therewith, a wiping mechanism, feed rolls having yielding tires adapted to feed sheets through the straightening, scrubbing and wiping mechanisms, a rinsing mechanism consisting of a reservoir, and a conveyer 80 for immersing sheets into a bath contained 85 in the reservoir and for removing them therefrom, combined wringing and planishing rolls, a drying mechanism consisting of an oven, and means for supplying heat to the oven, said mechanisms and rolls being 90 arranged for passage of sheets therethrough and substantially in the order named, and a conveyer operatively associated with the mechanisms for passing sheets consecutively therethrough. 95

15. In combination in a machine for renovating metal sheets, a straightening mechanism consisting of two straightening bars adapted to permit a sheet to pass between them, a scrubbing mechanism consisting of a brush, means for moving the brush over the sheet passing in engagement therewith, and a water feed pipe located adjacent to and adapted to distribute water on the brush, a wiping mechanism, a rinsing mechanism consisting of a reservoir, and a conveyor for immersing sheets into a bath contained in the reservoir and for removing them therefrom, combined wringing and planishing rolls, a drying mechanism, said mechanisms and said rolls being arranged for passage of sheets therethrough and substantially in the order named, and a conveyor operatively associated with the mechanisms for passing sheets consecutively therethrough. 115

16. In combination in a machine for renovating metal sheets, a straightening mechanism, consisting of two straightening bars adapted to permit a sheet to pass between them, a scrubbing mechanism consisting of a brush, and means for moving the brush over the sheet passing in engagement therewith, a wiping mechanism, a rinsing mechanism consisting of a reservoir and a conveyer for immersing sheets into a bath contained in the reservoir and for removing them therefrom, combined wringing and planishing rolls, a drying mechanism consisting of an oven, and means for supplying heat to the 120 125 130

oven, a buffing mechanism, said mechanisms and rolls being arranged for passage of sheets therethrough and substantially in the order named, and a conveyer operatively associated with the mechanisms for passing sheets consecutively therethrough.

17. A machine for renovating metal sheets, comprising straightening, scrubbing and wiping mechanism, and a conveyer for passing sheets consecutively through said mechanisms, said conveyer consisting of a series of rolls having tires of yielding material adapted to engage the sheets.

18. A machine for renovating metal sheets, comprising a sheet straightening mechanism consisting of two straightening bars adapted to remain stationary and to permit a sheet to be drawn between them, a scrubbing mechanism, and a drying mechanism operatively associated therewith, said mechanisms being arranged for consecutive passage of sheets therethrough.

19. In combination in a machine for renovating metal sheets, a sheet straightening mechanism consisting of two straightening bars adapted to remain stationary and to permit a sheet to be drawn between them, scrubbing, wiping, rinsing, wringing, planishing, and drying mechanisms arranged for passage of sheets therethrough and substantially in the order named, and a conveyer adapted to carry sheets through the machine and into operative relation with the mechanisms.

20. In combination in a machine for renovating metal sheets, a straightening mechanism consisting of two straightening bars adapted to remain stationary and to permit a sheet to be drawn between them, a scrubbing mechanism consisting of a brush and means for moving the brush over a sheet passing in engagement therewith, and wiping, rinsing, wringing, planishing, and drying mechanisms arranged for passage of sheets therethrough and substantially in the order named.

21. In a machine for renovating metal sheets the combination of a straightening mechanism, a wiping mechanism consisting of a strip of wiping material held in stationary yielding engagement with the sheets passing through the machine and adapted to permit the sheets to be slidily drawn from engagement therewith, and rinsing, wringing, planishing, and drying mechanisms arranged for passage of sheets therethrough and substantially in the order named.

22. In a machine for renovating metal sheets the combination of a straightening mechanism consisting of two straightening bars adapted to remain stationary and to permit a sheet to be drawn between them, a scrubbing mechanism, and a wiping mechanism consisting of a strip of wiping ma-

terial held in stationary yielding engagement with the sheets passing through the machine and adapted to permit the sheets to be slidily drawn from engagement therewith, and rinsing, wringing, planishing and drying mechanisms arranged for passage of sheets therethrough and substantially in the order named.

23. In combination in a machine for renovating metal sheets, a straightening mechanism consisting of two straightening bars adapted to remain stationary and to permit a sheet to be drawn between them, a scrubbing mechanism, a wiping mechanism consisting of a strip of wiping material held in stationary yielding engagement with the sheets passing through the machine and adapted to permit the sheets to be slidily drawn from engagement therewith, rinsing, wringing, planishing and drying mechanisms arranged for passage of sheets therethrough and substantially in the order named, and a conveyer adapted to carry sheets through the machine and into operative relation with the mechanisms.

24. In a machine for renovating metal sheets, the combination of a sheet straightening mechanism consisting of two straightening bars adapted to remain stationary and to permit a sheet to be drawn between them, a scrubbing mechanism, a wiping mechanism, a rinsing mechanism consisting of a reservoir, and a conveyer for immersing sheets into a bath contained in the reservoir and for removing them therefrom, and wringing, planishing, and drying mechanisms following the rinsing mechanism, all of said mechanisms being arranged for passage of sheets therethrough and substantially in the order named.

25. In combination in a machine for renovating metal sheets, a sheet straightening mechanism consisting of two straightening bars adapted to remain stationary and to permit a sheet to be drawn between them, a scrubbing mechanism, a wiping mechanism, a rinsing mechanism consisting of a reservoir, and a conveyer for immersing sheets into a bath contained in the reservoir and for removing them therefrom, wringing, planishing, and drying mechanisms following the rinsing mechanism and arranged for passage of sheets therethrough, said mechanisms being arranged in substantially the order named, and a conveyer adapted to carry sheets through the machine and into operative relation with all of the mechanisms.

26. In a machine for renovating metal sheets, the combination of a sheet straightening mechanism consisting of two straightening bars adapted to rotate to permit entrance of a sheet between them and to remain stationary to permit the sheet being drawn between them after cessation of ro-

5 tation, scrubbing, wiping, and rinsing mechanisms, combined wringing and planishing rolls, and a drying mechanism, said mechanisms and rolls being arranged for passage 6 of sheets therethrough and substantially in the order named.

27. In combination in a machine for renovating metal sheets, a sheet straightening mechanism consisting of two straightening bars adapted to rotate to permit of the entrance of a sheet between them and to remain stationary and permit the sheet being drawn from between them after cessation 10 of rotation, scrubbing, wiping, and rinsing 15 mechanisms, combined wringing and planishing rolls for receiving sheets from the rinsing mechanism, and a drying mechanism, the mechanisms and rolls being arranged for passage of sheets therethrough 20 and substantially in the order named, and a conveyer adapted to carry sheets into the machine and into operative relation with the mechanisms and rolls.

28. In combination in a machine for renovating metal sheets, a straightening mechanism consisting of two straightening bars adapted to rotate to permit the entrance of a sheet between them and to remain stationary to permit the sheet being drawn 25 from between them upon cessation of rotation, a scrubbing mechanism consisting of a brush, means for moving the brush over a sheet passing in engagement therewith, and a second means for yieldingly maintaining 30 the brush in engagement with the sheet, a wiping mechanism, a rinsing mechanism, combined wringing and planishing rolls, and a drying mechanism, said mechanisms and rolls being arranged for passage of 35 sheets therethrough and substantially in the order named.

29. A machine for renovating metal sheets, comprising a sheet straightening mechanism consisting of two straightening bars adapted to rotate to permit the entrance of a sheet between them and to remain stationary to permit the sheet to be drawn from between them upon cessation 45 of rotation, a scrubbing mechanism consist-

ing of a brush, means for moving the brush 50 over a sheet passing in engagement therewith, and a second means for maintaining the brush in yielding engagement with the sheet, a wiping mechanism, a rinsing mechanism, combined wringing and planishing 55 rolls, and a drying mechanism, said mechanisms and rolls being arranged for passage of sheets therethrough and substantially in the order named, and a conveyer adapted to carry sheets through the machine and into 60 operative relation with the mechanisms and the rolls.

30. In combination in a machine for renovating metal sheets, a straightening mechanism consisting of two straightening bars 65 adapted to rotate to permit the entrance of a sheet between them and to remain stationary to permit the sheet being drawn from between them upon cessation of rotation, a scrubbing mechanism consisting of a brush, 70 means for moving the brush over the sheets passing in engagement therewith, and a second means for yieldingly maintaining the brush in engagement with the sheets, a wiping mechanism consisting of a strip of 75 wiping material held in stationary yielding engagement with the sheets, a rinsing mechanism consisting of a reservoir, and a conveyer for immersing sheets into a bath contained in the reservoir and for removing 80 them therefrom, combined wringing and planishing rolls, a drying mechanism consisting of an oven, a means for supplying heat to the oven, said mechanisms and rolls being arranged for passage of sheets therethrough and substantially in the order 85 named, and a conveyer having feed rolls with yielding tires adapted to feed the sheets through the straightening, scrubbing, and wiping mechanisms, and to deliver the 90 sheets to the rinsing mechanism.

In testimony whereof, I have hereunto subscribed my name this 21 day of January, 1916.

CHARLES F. HAKE, Jr.
